UNITED STATES PATENT OFFICE.

RICHARD A. L. BLONDEL, OF BOSTON, MASSACHUSETTS.

DESIGN FOR AN INLET-VALVE CASING.

SPECIFICATION forming part of Design No. 24,347, dated May 28, 1895.

Application filed April 11, 1895. Serial No. 545,399. Term of patent 14 years.

To all whom it may concern:

Be it known that I, RICHARD A. L. BLONDEL, a citizen of the United States, residing at Boston, in the county of Suffolk and State of Massachusetts, have invented and produced a new and original Design for an Inlet-Valve Casing, of which the following is a specification, reference being had to the accompanying drawings, in which—

10 Figure 1 is a side view of the ball-cock or valve casing, showing my design; and Fig. 2 is another side view. Fig. 3 is a plan view.

15 The leading feature of my design is a horizontal flange, or extension, of the body of the valve casing, in connection with a vertical, cylindrical offset of the latter, which is arranged beneath and joined with said flange, as best shown in Fig. 1.

In the drawings, *d* indicates the flange, or extension, having lateral swells, or projections, *c*, at its inner end or base, and *b* is the cylindrical offset, which parts (*d*, *c*, *b*) are united with the cylindrical body of the valve casing, *a*.

The casing is intended for inlet valves (known as ball-cocks) of water-tanks.

What I claim is—

The design for an inlet valve casing, substantially as shown and described.

RICHARD A. L. BLONDEL.
